United States Patent

Des. 236,777
Patented Sept. 16, 1975

236,777

DISPLAY UNIT

Roland E. Loomis, Menlo Park, Calif., assignor to House
of Health, Inc., Santa Clara, Calif.

Filed July 16, 1973, Ser. No. 379,775

Term of patent 14 years

Int. Cl. D20—02

U.S. Cl. D6—85

Fig. 2

Fig. 1

Fig. 3

Fig. 4

FIG. 1 is a perspective view of a display unit showing my design;

FIG. 2 is a front plan view of the design of FIG. 1, it being understood that the back of the design is the same as the front;

FIG. 3 is a side elevation view of the design of FIG. 1, it being understood that both sides of the design are the same; and

FIG. 4 is a top plan view of the design of FIG. 1, it being understood that the bottom of the design is the same as the top.

I claim:

The ornamental design for a display unit, as shown and described.
